CLAIM

We claim the ornamental design for a drywall cart, as shown and described.

DESCRIPTION

FIG. 1 is a perspective view of a drywall cart showing our new design;

FIG. 2 is an elevation view thereof;

FIG. 3 is another elevation view taken from ninety degrees relative to FIG. 2;

FIG. 4 is a top plan view thereof; and,

FIG. 5 is a bottom plan view thereof.

The broken lines in the figures are included for the purpose of illustrating portions of the cart and form no part of the claimed design.
